CLAIM

The ornamental design for a clipper, as shown and described.

DESCRIPTION

FIG. 1 is a top perspective view of a clipper in accordance with the present design;

FIG. 2 is a top plan view thereof;

FIG. 3 is a bottom plan view thereof;

FIG. 4 is a rear elevation view thereof;

FIG. 5 is a front elevation view thereof;

FIG. 6 is a right elevation view thereof; and,

FIG. 7 is a left elevation view thereof.

(Continued)

The broken lines depict unclaimed features of the clipper, included for illustrative purposes only, and form no part of the design claim.

1 Claim, 4 Drawing Sheets
